UNITED STATES PATENT OFFICE.

GEORGE A. DUBOIS, OF NORFOLK, VIRGINIA, ASSIGNOR TO DUBOIS GASIFIER CORPORATION, OF NORFOLK, VIRGINIA, A CORPORATION OF VIRGINIA.

GASIFIER FOR INTERNAL-COMBUSTION ENGINES.

1,197,110.

Specification of Letters Patent.

Patented Sept. 5, 1916.

Application filed January 29, 1914, Serial No. 815,246. Renewed February 3, 1916. Serial No. 76,071.

To all whom it may concern:

Be it known that I, GEORGE A. DUBOIS, a citizen of the United States, residing at Norfolk, in the county of Norfolk and State of Virginia, have invented certain new and useful Improvements in Gasifiers for Internal-Combustion Engines, of which the following is a specification.

My invention relates to gasifiers of liquid hydrocarbon for internal combustion engines.

The object of the invention is to provide means whereby liquid fuel, more particularly kerosene or other heavy carbon oil may be vaporized and then transformed into a gas for operating internal combustion or hydrocarbon engines or motors.

Further objects and advantages will be more fully described herein and specifically pointed out in the hereunto annexed claims recourse being had to the accompanying drawing forming a part of this specification in which:—

Figure 1 is an elevation of the assembled device with a portion of shell or casing broken away to show a part of its interior. Fig. 2 is a sectional plan of the interior of the lower section or element of the gasifier. Fig. 3 is a cross section on the lines 1—2 in Fig. 1. Fig. 4 is an end view of the discharging or exhaust end, and Fig. 5 shows connection to the gasifier with a gasolene carbureter when it is desired to use both kerosene and gasoline.

In the drawing like reference numerals indicate similar parts in all the several views.

1 is the upper section of the casing or shell and is provided with a flange or flanges and a head or cover, as at 2.

3 is the lower portion or half of the casing and is adapted to be united to the upper section 1 by means of suitable bolts passing through ears or lugs thus securing the two halves firmly together as shown in Fig. 1.

4 is an enlarged portion or expansion end of the two sections 1—3 and is arranged so as to be eccentric to the axis of the cylinder or barrel part of the united sections 1—3.

5 is the hydrocarbon or liquid fuel intake for supplying the device with kerosene or other carbon oil.

The oil when it enters the gasifier is first vaporized and then changed to a gas, as will be described hereafter.

6 is the gas outlet or throttling discharge for the gas which is led to the gas engine for its supply of fuel. The outlet 6 is provided with a suitable controlling valve so that the supply may be regulated at will. By suitable means I may arrange to have a sliding joint for the discharge pipe so that it may be entered and withdrawn from the portion 4 for convenience in applying my device to an engine.

7 is an inwardly opening air valve for mixing a sufficient amount of air with the gas which is necessary for its combustion. The valve 7 is provided with suitable spring and adjustment means for the proper regulation of the air.

8 are a series of semi-circular or elliptic baffle plates arranged at suitable intervals in each half of the casing, 1—3, but when the two sections are united they form circular or eccentric deflector rings or plates and surround the hereinafter described exhaust pipe or heating flue.

9 is the heater pipe or exhaust flue passing through the casing 1—3 and having outwardly extending ends, as at 10 and 11, the said ends being the exhaust inlet from an engine and the other the exhaust discharge to the atmosphere, respectively.

12 are a series of circular or elliptic shaped flanges, rings or baffle plates formed upon the pipe or heater flue 9 and are adapted to come between the plates or rings 8 and form passages therewith which act as expansion pockets for the vapor and gas between them and under the latter, as at 13 in Fig. 2. By this means a continuous sinuous passage is formed from one end of the casing 1—3 to the other permitting the oil to come in contact with surfaces of various temperatures as to first vaporize the oil and then gasify it.

14 is an enlargement nearly surrounding the discharge end of the heater pipe 9 and having a flange 15 and is adapted to conform to and be attached to a similarly shaped cap 16 which surrounds the pipe 9 exterior to the discharge end of the casing or cylinder 1—3. The portions 14 and 16 form a water jacket for cooling the gas and to prevent spontaneous combustion thereof.

17 are nuts adapted to secure the casing 1—3, the heater pipe 9, and the flange and cover 2 firmly together.

18 is the cooling water inlet to the water jacket above mentioned, and 19 is the water discharge or overflow from the same, the latter being shown by dotted lines in Fig. 1 and discharges into the pipe 9 at or near the outlet 11.

20, shown by dotted lines in Fig. 1, and full lines in Fig. 4, is the gas outlet which may replace that at 6 in applying the device 10 to an engine and where it is desirable or necessary to use a side connection instead of at the bottom as in Fig. 1.

21 is a priming cup connection for the oil in cases where the device is first started up 15 and generally precedes the full opening of the oil inlet or supply 5.

When starting up the gasifier it is necessary to heat the same and this I do by a suitable torch or burner attachment but 20 such details I do not show they being no part of my invention. The exhaust of the engine passing through the flue or pipe 9 heats the oil and gas in the circuitous path along the hot retort plates 8 and 12.

25 As shown, the pipe 9 does not pass through the centers of the plates 12, nor are the passages, as at 13, in the centers of the plates 8, though I may arrange them in concentric order instead of eccentric, as may be 30 desired. When the plates are eccentrically disposed to the pipe 9 there is more space above the pipe than below (Fig. 3), so as to allow full expansion of the gas in its path to the outlet.

35 Between a suction impulse of the engine to be supplied, the oil is vaporized and drawn through the described passages to the middle portion of the same and held until a previous supply of the gas is ex- 40 ploded in the engine after which the oil is gasified in time for the next suction impulse of the engine and is consequently drawn to complete the cycle of operation of the engine continuously. At the left hand end of 45 the gasifier the oil enters and is vaporized, at the middle thereof the oil changes into a true gas and at the right hand end, as at 4, the gas is cooled and mixed with air preparatory to being discharged; hence the de- 50 vice has three stages of operation before the transformed oil reaches the engine to be supplied.

As shown in Fig. 5, the valve connection, as at 6, may be connected to a T or other 55 pipe. The vertical member 22 may be connected to an ordinary carbureter, as at 23, whose outlet 24 is connected to the cylinder of a hydrocarbon engine 25. In this manner the kerosene or heavy carbon oil may 60 be supplemented by gasoline vapor, at will.

I claim:

1. A device of the class described, composed of a casing or cylinder having rings cast thereon, a cylinder or heater flue having rings thereon, said rings adapted to 65 come between the first named rings to form annular circuitous passages, and a water jacket formed on said flue and disposed partly within and partly without said casing. 70

2. A device of the class described, composed of a casing or shell provided with a series of baffle rings or plates, an eccentric or offset water chamber at one end of the casing, a heater flue passing through the 75 casing provided with baffle rings or plates adapted to form passages with the first named rings or plates, and throttle valve controlling means for the gas outlet of said casing. 80

3. A device of the class described, composed of a casing having eccentrically arranged baffle plates or rings therein, a heater flue arranged to be surrounded by 85 said baffle plates or rings, said flue having eccentrically arranged plates or rings disposed to come between the first named plates or rings, an eccentric enlargement on the casing, a water cooler or jacket formed by said eccentric end and one end of said 90 heater flue, and throttle valve controlling outlet means for said casing.

4. A device of the class described, composed of an outer casing, an inner tube, a series of baffles disposed between said casing and said tube, said casing having an inlet opening at one end and a gas discharge outlet at the other end, and a water jacket disposed between the casing and the tube at the discharge end of the casing for cooling 100 the gas. 95

5. A device of the class described, composed of an outer casing, an inner tube, a series of baffles disposed between said casing and said tube, said casing having an inlet opening at one end and a gas discharge outlet at the other end, and a water jacket disposed between the casing and the tube at the discharge end of the casing for cooling 105 the gas, said water jacket having an inlet 110 for water and an outlet discharging into the inner tube.

In testimony whereof I have hereunto affixed my signature in the presence of two witnesses.

GEORGE A. DUBOIS.
